UNITED STATES PATENT OFFICE.

EMIL BLOSSFELD, OF SAN FRANCISCO, CALIFORNIA.

LEATHER BELTING.

1,104,341.

Specification of Letters Patent. Patented July 21, 1914.

Application filed July 8, 1912. Serial No. 707,454.

To all whom it may concern:

Be it known that I, EMIL BLOSSFELD, a citizen of the United States, residing in the city and county of San Francisco and State 5 of California, have invented new and useful Improvements in Leather Belting, of which the following is a specification.

This invention relates to leather belts and the method of manufacturing the same.

10 It is the object of this invention to produce a leather belt of great strength and durability, and in which the use of stitching and rivets may be dispensed with.

Another object is to produce a leather belt 15 of equal strength throughout its length and so arrange the joints of adjacent strips of leather that they will not be loosened or separated by contact with the pulleys or by air resistance.

20 Another object is to construct a belt of a single thickness of leather by so splitting and arranging the leather strips as to form a belt of the thickness of the hide of which the leather is formed, but of greater strength 25 and durability than can be obtained by forming the belt of connected unsplit lengths of leather, as now commonly employed in the manufacture of belts.

In carrying out this invention I have 30 taken advantage of the well known fact that strips of leather cut from the hides of animals approximately parallel with the spine, as is common in leather belt construction, are of greater strength on the edge nearest 35 the spine. Belts formed of single strips of leather taken from the hide in this manner, being of greater strength on one edge than on the other, the weaker edge has a tendency to stretch so as to cause the belt to become 40 uneven and irregular, with the result that its efficiency is greatly impaired. I have also taken advantage of the fact that leather possesses a grain of a fibrous nature, running parallel with the spine, by splitting the 45 leather so as to separate it into two layers and then turning these layers in opposite direction in relation to each other and cementing them together so that the grain of one layer will extend in an opposite direction 50 to the grain of the other layer.

Other features employed in the construction of my belt will be set forth in the following specifications; reference being had to the accompanying drawings, in which—

55 Figure 1 is a perspective view showing separate strips of leather as cut from a hide,

in readiness for being converted into a belt, and illustrating the first step employed in my process. Fig. 2 is a similar view showing the leather strips as connected together at their ends, illustrating the second step in 60 my process. Fig. 3 is a similar view depicting the manner of splitting the leather strip, illustrated in Fig. 2, which constitutes the third step in my process. Fig. 4 is a perspective view of the completed belt. Fig. 5 65 is a diagram showing the application of a belt constructed in accordance with this invention.

In carrying out this invention I take 70 strips of leather as indicated at A and B in the drawings, which strips are preferably cut from the hide of an animal approximately parallel with the spine, of any suitable width as is common in the manufacture 75 of leather belts. These strips are arranged in longitudinal alinement with each other, flesh side down, with the edges of the greatest strength on the same side. The strip A is then beveled at its end upon the underside, as indicated by dotted lines a and the strip B is beveled at its end on its upper face, as indicated by the dotted line b. The two ends of the strips A and B are then placed as illustrated in Fig. 2, and are securely cemented together by any suitable adhesive material, and in any desired manner, forming a joint as indicated at 80 2. A number of strips A and B are thus connected together to form a continuous 85 strip of leather of any desired length. The strip thus formed is then split longitudinally, as illustrated in Fig. 3, so as to separate it into two layers; the underside of the lower layer being the flesh 90 side, and the upper face of the upper layer 95 being the hair side of the hide. The upper layer is then turned end for end, so as to reverse the direction of its grain in relation to the grain of the lower layer and to dispose the strong edge of the upper layer on the opposite side of the belt to the strong edge of the lower layer; the upper strip is then secured to the lower strip, preferably by cementing the two strips together by a 100 suitable adhesive material; the joints 2 being staggered in relation to each other as shown in Fig. 4. It will be noted by reference to this figure, that by reversing the upper and lower layers in relation to each 105 other, the lap of the joints 2 on the upper and lower layer will now extend in the same

direction. The strips thus formed may now be cut in suitable lengths and laced together at their ends to form a continuous belt as indicated in Fig. 5.

5. By forming a belt in the manner described it will be of equal strength on its opposite edges so that the tendency or inclination of the belt to stretch more on one edge than on the other will be obviated. The strength of 10 the belt throughout its length will be greatly increased by reason of the grain of the upper section of the belt extending in a direction opposite to the grain in the lower section thereof. By staggering the joints 2, the belt 15 will not be perceptibly weakened at this point, as the layer opposite the joint, serves as a reinforce.

A particular advantage to be derived by 20 forming the joints 2 in the manner described so that the laps on opposite sides of the belt will extend in the same direction, lies in the fact that, when the belt is run upon the pulley in the direction of the lap, as indicated in Fig. 5 in which 3 indicates a driving 25 pulley and 4 a driven pulley, the frictional engagement with the pulley 4 will not tend to separate the laps of joints 2 on the inner side of the belt.

30 One of the greatest difficulties commonly met with in the ordinary leather belts is the wear upon the joints of adjacent sections; this wear being due either to the action of the pulley tending to peel or separate the 35 lap, or a similar action occasioned by the belt traveling with the lap against the air. This difficulty is more commonly met with where the joints 2 extend continuously through the belt as indicated in Fig. 2, for the reason that if the belt is positioned on 40 the pulleys so that the lap on the lower edge of the belt will run therewith, the lap on the

outer edge of the belt will catch the air and in time become loosened and worn at this point. The reverse is also true where the belt is run so that the lap on the outside will 45 run with the air, wherein the lap on the inner side will be run in opposition to the pulley with the consequent tendency to peel up and become loosened. By reference to Fig. 5, it will be seen that by staggering the 50 joints 2 and forming them so that the laps on the upper and lower sides of the belt will extend in the same direction, that where the belt is run in one direction the above difficulties will be overcome. 55

Having thus described my invention, what I claim and desire to secure by Letters Patent, is—

A leather belt comprising superposed sheets of leather, the sheets being composed 60 of strips cut parallel with the length of the hide, said strips being split and superposed in a reversed end to end relation with the grain of one sheet extending in the opposite direction from the grain of the other sheet, 65 the joints of one sheet lying intermediate the joints of the other sheet, the forward ends of each of the outer sheets being tapered with the inner ends of the taper in advance 70 of the outer end of the taper so as to lie under the next preceding sheet, and the forward ends of each of the inner sheets being tapered with the end of the taper adjoining the layer above in advance of the end of the taper on the traction surface of the belt. 75

In testimony whereof I have hereunto set my hand in the presence of two subscribing witnesses.

EMIL BLOSSFELD.
